CLAIM

The ornamental design for a pet car seat cover, as shown and described.

DESCRIPTION

FIG. 1 is a front, right and top perspective view of a pet car seat cover showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an alternate configuration of the top plan inner view thereof; and,

FIG. 9 is an enlarge view of FIG. 4.

The broken lines shown in the figures are for the purpose of illustrating portions of the pet car seat cover that forms no part of the claimed design.
